SPARK PLUG

Melville F. Peters, Beltsville, Md., and Fred I. McCarthy, New York, N. Y.

Application June 5, 1942, Serial No. 445,938

14 Claims. (Cl. 123—169)

This invention relates to improvements in spark plugs for automotive engines of the gas type using spark plug ignition.

The improvement herein described consists of a novel structure in which metallic powder is disposed adjacent the spindle shank which powder when compacted prevents gases from passing into the interior of the spark plug, and also serves to dissipate heat from the central spindle shank outwardly.

The invention also consists in providing a copper sleeve with a wedge shaped member around the spindle shank in order to direct the component of forces when the powder is compacted, so as to close any passage and thereby prevent gases from passing into the spark plug.

The invention also consists in equalizing the heat at the spark end, by the provision of a cut-out, and a heat distributing sleeve on the spindle shank.

Also the invention consists in providing a spark gap at one end of the spindle shank at the interior of the spark plug which has a distinct relation to the spark gap at the exterior end of the spark plug, means being provided to determine the size of the gap.

The invention contemplates as alternatives the use of a helical spring to surround a mica sleeve enclosing the spindle shank, and then to be compacted with the powder; spaced conically shaped washers or rings to augment the compacting action when the powder is compacted, and a conically shaped insulating spacer resulting in a conically shaped space to assist the heat exchange action at the spark gap end of the spark plug. Either one or all of these may be used.

The invention will be more fully described hereinafter, embodiments are shown in the annexed drawing, and the invention will be finally set forth in the claims.

In the accompanying drawing,

Fig. 1 is a vertical central section through an embodiment of our spark plug;

Fig. 2 shows an enlarged fragmentary central section of the metallic powder portion of the embodiment shown in Fig. 1;

Fig. 3 is a fragmentary section showing the force components;

Fig. 4 is a central section of the spark plug end, and embodying various alternatives;

Fig. 5 is a central section at the top end of the spark plug shown in Fig. 1, showing the initial spark gap determinative of the spark gap at the sparking end of the plug;

Fig. 6 is a central section of the bottom end of the spark plug of Fig. 1;

Fig. 7 is an electric diagram showing the relationship of the initial spark gap to the final spark gap; and

Fig. 8 is a chart showing three curves, the

curve A resulting from our improved invention.

Similar reference characters have been used to indicate like parts throughout the several views.

5 Referring to the drawing, and more particularly to Fig. 1, the usual spark plug is there shown, with one improvement embodied therein. The present improvements consist in providing the central spindle shank 10 which terminates at 10 its lower end at 12 at the exposed end of the spark plug, and which is cylindrical in shape. A cylindrical sleeve 13 of mica or the like, or a mica cigarette, extends along the length of the spindle shank 10. A sleeve 18 of mica or the like, is concentric with the mica cigarette. The outer sleeve 18 terminates at its upper end 19 and is held to the body portion 20 of the upper shell by upsetting the body portion as shown, and the lower end of the sleeve 19 rests upon a shoulder 21 of the lower shell. The upper and lower shells are connected by screw thread 21a. The lower shell 21a has a conical bore 22 and a filling of powder indicated by 23 fills the space circumferentially around the spindle shank 10 and within the bore 22. After shaking the powder particles to fill all parts, the powder particles are compactly squeezed together by high pressure so as to make a substantially integral metallic layer, without air interstices, so that gases are prevented from passing therethrough, thereby protecting the inner structure of the spark plug from gases. This compacted copper powder also aids in dissipating heat from the central spindle shank to the outer part of the plug.

35 The use of the metallic powder around a portion of the insulating material or cigarette sleeve 13 provides a close packing and obliterates gas leakages and aids in the heat conductivity in the lower shell. The powder is packed tightly

40 and aids in the displacement of heat to the outer lower shell. Above the compacted powder a series of mica washers or rings 17 are compacted together, on the top of which an insulating ring 17a is provided, which is slightly larger than the rings 17 so that when compressed therein the rings 17 are held in permanent position. Other fastening devices may be used.

45 In Fig. 2 is shown an enlarged portion of part of Figure 1. The important step is the use of copper powder, in combination with enclosures for the same, to enable such pressures to be applied to the powder that it appears to act as a fluid, and forms a solid. The enclosures consist of the interior of the shell, preferably of conical wall 22, and the exterior of the spindle shank 10, and a conically shaped member 59a to direct the forces in such a direction as to obtain a secure gas seal. The spindle shank 10 is surrounded by a mica sleeve or mica cigarette 13, and also by a thin copper sleeve 13a preferably

part of the cone shaped base member 59^a. The base member 59^a may be integral with the copper sleeve 13^a, as shown, or in two separate parts. The copper sleeve may extend clear up in one piece almost to the end of the spindle shank, or only to mica washers. The copper sleeve may extend almost to the end of the spindle shank, to efficiently fill the powder, and then may be cut off about where the mica washers are placed. Or the copper sleeve may terminate at the mica washers and another sleeve added to assist in the filling and it can then be withdrawn. The irregularities of the exterior surface of the copper sleeve, and the irregularities of the interior surface of the metal of the casing (visible by 15 magnification) are filled in by the small particles of powder and are forced closed by pressure, and at the same time, the mica cigarette adjacent the copper sleeve is pressed against the spindle shank, in a manner that such particle pressure 20 presses the mica intimately against the exterior surface of the spindle shank. The mica cigarette being somewhat pliable fills the irregularities of the spindle shank and copper sleeve. The preliminary pressure applied gradually permits this orientation, and the further pressure consolidates these actions, to the extent that when the entire pressure action has been completed, there cannot be any return movement, the inherent energy applied holding the parts described 30 in this close fitting relationship the powder having become a solid. This is further accentuated by the inward component of the force of the downward axial pressure acting inwardly against the outer surface of this spindle shank, thereby securing a still further positive anchorage. A gas tight seal along the outer surface of the spindle shank and the inward surface of the shell is thereby provided.

In Fig. 3 is a detail view, showing how the powder presses against the inclined wall 22, and a component acts to transmit downward force to an angular force against the exterior of the spindle shank, which as stated is enveloped by the mica cigarette and this cigarette is covered by the copper sleeve 13^a.

In Fig. 5 an enlarged view of the top of the spindle shank is shown. The top is cut away in the general shape shown so as to form a gap or space 44. The conducting T-shaped member 41, has its vertical leg 42 surrounded by a refractory insulating L shaped tubing 43, hollow axially, and the axial tube thereof seals into the cut out gap 44^a of the spindle. A washer 45 of metal also holds the mica washers 17 in place, and the washer 45 has its bore 45^a surround the outer circumference of the end 10^a of the spindle shank 10. The mica cigarette 13 terminates at its upper end with below the end 10^a. This gap 44 enables the voltage at the sparking gap to build up more rapidly than if this series gap were not present.

In Fig. 7 an electric diagram is shown to illustrate the formula which is applicable, to wit: $V_1 C_1 = (C_1 + C_2) V_2$, where V_1 corresponds to the series gap 44, and the gap V_2 corresponds to the sparking gap 46.

The curve of Fig. 8 shows time as the abscissa and voltage as the ordinate, the curve A representing the best form with a break down at the expenditure of the least time, much better than curves B or C of the prior art.

Figs. 1, 4 and 6 present views showing the sparking head. The important feature is to provide means to keep the metallic parts at sub-

stantially even and cool temperatures. The refractory material ring 50 of Fig. 1 is of a size to determine the length of the spark gap V_2 or 46. Or the ring in combination with other refractory material, such as mica washers, may be used. The structure is arranged so that the member 51 is not too cold, and the sparking end of the spindle shank is not too hot. By equalizing the rate of heat flow in the two members, the thermal qualities of the plug are greatly improved. In Fig. 1, the spacing ring 50 is substantially cylindrical, but in Fig. 4, it is conical as at 50^a, in Fig. 4, in which case an airspace 50^b results, which aids in increasing the surface flash over distances between the spindle head 12 and the part 52. Also, the shell is provided with a deep cut out 51, to keep 52 warm enough. Finally, the lower end of the spindle shank 10 from the end to where the copper powder filling ends at the top has its outer peripheral portion ground off and replaced by a copper sleeve, or preferably by a copper plating 59, which conducts the heat away from the tip end upwardly, and distributes it at a place where such distribution is harmless.

As an alternative, there is shown in Fig. 4, a series of metal rings or washers 60, of wedge-shaped cross-section, around which the powder flows, and also a helical spring 61 to hold the mica cigarette, and as before explained, a conical member 50^a of mica or ceramic instead of a cylindrical member 50, with an air space 50^b. Either one or all of these alternative features can be placed in the embodiment of Figure 1.

In Fig. 6, the depth of the cut out 51 prevents the device from fouling; the deeper the cut out the hotter part 52 will be and the more resistant will it be to fouling. The refractory 50 as mica or ceramic is used to limit the gap 46, protecting the mica cigarette from drawing gases from the engine, and it is placed in such a manner that if it cracks, the pieces will not get into the engine.

We have described several forms of our invention, but obviously various changes may be made in the details disclosed without departing from the spirit of the invention as set out in the following claims.

What is claimed is:

1. In a spark plug having a central spindle shank the end of which forms one terminal, a layer of compressed metallic powder surrounding said spindle shank, said compressed powder obstructing the passage of gases but assisting the passage of heat, a metallic sleeve with a wedge-shaped member surrounding said spindle shank, the wedge-shaped member being adapted to direct a component of force against said spindle shank.

2. In a spark plug having a central spindle shank the end of which forms one terminal, a mica cigarette surrounding said spindle shank, a layer of compressed metallic powder surrounding said spindle shank and the mica cigarette, said compressed powder obstructing the passage of gases but assisting the passage of heat, a metallic sleeve with a wedge-shaped member surrounding said spindle shank, the wedge-shaped member being adapted to direct the component of force against said spindle shank, the lower end of the spindle shank being copper or other metal enclosed to conduct heat from the spark end inwardly of the spark plug.

3. In a spark plug having a central spindle shank the end of which forms one terminal, the spark plug end having a spark gap, and an insu-

lating member determining the size of the gap, said insulating member being conical and providing a conically shaped cooling space.

4. In a spark plug having a central spindle shank with a spark gap at its outer end, a mica cigarette surrounding the spindle shank, a wedge-shaped bore in the body of the spark plug, a wedge-shaped base member in said bore surrounding the mica cigarette, a copper sleeve surrounding said mica cigarette above the base member, a compacted powder in said bore compressed by high pressure to a solid filling said bore and pressing against said wedge-shaped base member, copper sleeve, mica cigarette and spindle shank, and mica washers above said solid compact.

5. In a spark plug having a central spindle shank with a spark gap at its outer end, a mica cigarette surrounding the spindle shank, a wedge-shaped bore in the body of the spark plug, a wedge-shaped base member in said bore surrounding the mica cigarette, a copper sleeve surrounding said mica cigarette above the base member, a compacted powder in said bore compressed by high pressure to a solid filling said bore and pressing against said wedge-shaped base member, copper sleeve, mica cigarette and spindle shank, mica washers above said solid compact, and a helical spring around said mica cigarette.

6. In a spark plug having a central spindle shank with a spark gap at its outer end, a mica cigarette surrounding the spindle shank, a wedge-shaped bore in the body of the spark plug, a wedge-shaped base member in said bore surrounding the mica cigarette, a copper sleeve surrounding said mica cigarette above the base member, a compacted powder in said bore compressed by high pressure to a solid filling said bore and pressing against said wedge-shaped base member, copper sleeve, mica cigarette and spindle shank, mica washers above said solid compact, a helical spring around said mica cigarette, and wedge-shaped rings compacted within said powder compact.

7. In a spark plug having an outer shell with a bore, a central spindle shank disposed centrally of the bore in spaced relationship to the bore of the outer shell, a lining member surrounding said shank at least along a length corresponding to the bore of the shell, and a layer of solid connecting material formed by pressure from a powder disposed between the shell bore and shank, said solid layer, shell and shank being substantially one mass to prevent the passage of gases, but permitting the passage of heat.

8. In a spark plug, a shank with a cutout at its spark gap end, a central spindle shank having an end to form a spark gap with the shell and having a cutout, and an insulating member in said cutouts disposed transversely to the spark gap, the length of the cutouts and insulating member therein being determinative of the length separating the shell and spindle to form the spark gap.

9. In a spark plug, a shell with a cutout disposed longitudinally thereof, a central spindle having a cutout disposed longitudinally thereof, the shell and spindle having ends to form a spark gap, an insulating material layer surrounding the spindle to insulate the shell from the spindle, and a second insulating material layer disposed

between the first layer and the spark gap to protect the first layer from the effects of any gases passing through the spark gap.

10. In a spark plug having a central spindle, one end of which forms one terminal of a spark gap and having a bore centrally disposed in the end of the spindle remote from its spark gap end, said bore having a bottom, a conducting member having a projection entering said bore and in spaced relation to said bottom, and an insulating layer between the wall of said bore and said projection and lining the walls of the bore to confine the spark between the end of the projection and bottom of the bore and prevent it from contacting with the walls of the bore.

11. In a spark plug, a shell having a bore, a central spindle shank the end of which forms one terminal, and spaced from the wall of said bore, a layer of solid metal pressed tightly against the spindle and wall of the bore, and substantially integral therewith, to prevent the passage of gases between the metal, spindle and layer, but permit the passage of heat, and means at the spark gap end of the shell and spindle 20 consisting of a cutout in the shell forming a free space transversely across the spark gap formed by the shell and spindle, to enable the remaining part of the shell to distribute the heat in order to decrease the amount of heat 25 passing through the layer of solid material.

12. In a spark plug, an outer shell having a bore, a spindle spaced from the walls of the bore, a solid material pressed between the walls of the bore and spindle to be substantially integral 30 therewith to prevent the passage of gases, and a gas-tight seal at the spark end of the spindle disposed within the shell and spindle at the spark gap formed between the shell and spindle.

13. In a spark plug, a metal shell having a bore and a shoulder, a metal spindle centrally of said bore and spaced from the walls of the bore, an insulating material sleeve surrounding said spindle from end to end thereof, a compacted powder in said bore compressed by high pressure to a solid filling the space between the spindle 40 sleeve and wall of the bore in the shell, and pressed against said shoulder.

14. In a spark plug having an outer shell member with a cylindrical bore and with a spark plug terminal at one end thereof, a central cylindrical spindle shank terminating in another terminating spark plug terminal spaced from the first-named terminal, said spindle disposed in spaced 50 relationship within said shell centrally of its bore, said outer shell also having a conical circumferential wall adjacent said cylindrical bore, an insulating member around the central spindle at least the axial length of the bore and the axial length of the conical wall leaving a conical space between the insulating member and the shell member, a layer of solid metal in the space between the insulating member and said conical wall, and insulating means disposed against the top of the solid metal layer between the outer 60 member and spindle, said shell, solid member, insulating lining and shank being substantially one mass to prevent the passage of gases but permitting the passage of heat.
